WALL BED

George A. Stackhouse, Oakland, Calif., assignor
to L. A. Young Spring & Wire Corporation,
Detroit, Mich.

Application February 12, 1932. Serial No. 592,595

7 Claims. (Cl. 5—172)

The main objects of this invention are:

First, to provide an improved wall bed having a supporting mechanism associated therewith for allowing the bed to be moved through an opening considerably narrower than the bed.

Second, to provide a mechanism of this character in which the bed is centrally supported so that it is balanced on its supports.

Third, to provide a mechanism of this type which is simple and compact yet strong and rugged and which, while connected to a support at only two points, carries the bed at its center throughout the entire cycle of operation of the device.

Objects relating to details and economies of my invention will appear from the description to follow. The invention is defined and pointed out in the claims.

A structure which is a preferred embodiment of my invention is illustrated in the accompanying drawings, in which:

Fig. 1 is a fragmentary perspective view of my improved wallbed associated with a closet having a relatively small door opening.

Fig. 2 is a fragmentary horizontal section on a line corresponding to line 2—2 of Fig. 6, the dotted lines indicating the various positions of the bed as it is moved through the door opening.

Fig. 3 is an enlarged fragmentary perspective view of the lower end of the supporting mechanism moved to about one-fourth open position.

Fig. 4 is a similar view showing the relation of the parts with the bed in approximately half open position.

Fig. 5 is a similar view showing the relation of the parts in full open position.

Fig. 6 is a fragmentary view sectioned mainly through the base of the supporting mechanism, and

Fig. 7 is a fragmentary perspective view of a modified form of the lower supporting mechanism.

Referring to the drawings, numeral 1 indicates a wall having a door opening 2 leading to a closet 3. The opening 2 is provided with a door frame 4 for the conventional door 5. The frame 6 of the wallbed 7 is provided with upper and lower frame supporting brackets 8 and 9 which have downwardly facing socket bearings 10 coacting with the upwardly projecting pins 11 on the outer ends of the supporting arms 12 and 13. These supporting arms have downwardly projecting bearing pins 14 which engage the upwardly facing socket bearings 15 of the door frame bracket 16 and the floor plate 17. The diagonal strut 18 is connected to the upper arm adjacent its inner end and to the lower arm adjacent its outer end, thereby providing a rigid bracing connection for the arms and compelling them to swing together as a unit. Thus sup-

ported, the arms swing about their pivots and the bed frame is pivotally mounted on the arms.

The bed frame brackets are secured to the bed frames so that the pivots of the bed frame on the arms are centrally of the frame which balances the frame and avoids the necessity of legs at one side of the attached end of the bed frame as is common practice in structures of this character in which the frame pivots are commonly at one side of the center in order to enable the frame to be moved through a door opening.

The movement of the bed frame on its pivots on the arms is controlled by a mechanism comprising the lever 19 which is pivotally connected at its inner end to the lower arm 13 adjacent its inner end, the lever being mounted on the pivot 20 and disposed on the underside of the arm 13 so that the arm may swing over it. The lever is provided with a follower roller 22 carried by the stub shaft 21, a ball bearing being preferably provided for this follower roller.

The outer end of the lever 19 is connected to the bed frame by means of the link 25, the link being pivoted at 24 to the lever and at 26 to the bed frame.

The floor plate 17 is provided with a flange-like cam 27 having a straight portion 28 at its inner end, a flange 28' being arranged in spaced relation to this straight portion of the flange to provide a throat adapted to receive the cam follower when the bed is in its completely collapsed position, this serving to prevent oscillating movement of the bed on its pivots on the arm; that is, holding it in that collapsed position until the bed is manually manipulated to swing it outwardly through the door opening.

This arrangement gives a compound movement to the bed; that is, the movement resulting from the swinging of the supporting arms and the movement resulting from the pivoting of the bed on the arms, this movement being such that the bed can be swung through a relatively small opening and permitting the connection of the bed at a central point.

The lever 19 has an offset at its inner end which permits its pivotal connection to the arm to swing to substantially opposite sides of the pivot for the arm—see the dotted line position in Fig. 2.

In operation, the guide means permits the bed to be swung first through an arc of about 80° about the pivots at the outer ends of the upper and lower arms. The dotted lines 29 of Fig. 2 illustrate the bed in this position. The frame is then swung about the pivots at the inner ends of the arms through an arc of about 35° to the position illustrated by the dotted lines 30. Finally, the bed is swung about the inner and outer vertical axes to the fully opened position illustrated by the dotted lines 31. The entire movement of the bed in passing through the door

opening 2 is controlled by the guiding means. In this movement, the bed is supported at all times at its center and freely passes through the door opening. By reference to Fig. 2, it will be observed that when the bed is in the closet 3 and when the bed is in the room, there is sufficient room between the bed and the door frame to permit a person to enter and leave the closet 3 without disturbing the bed.

10 In the modification illustrated in Fig. 7, the socket member 15' of the floor plate 17 is provided with an upstanding plate-like bracket 16' which is secured to the door frame. This structure provides a stronger lower supporting mechanism, the lower arm 13 being pivoted to the socket member 15'.

It will be appreciated that I provide a control mechanism which is supported at two points only and which supports and controls the movement 20 of the bed through the door opening. With my improved apparatus, a 4'x4' bed may be conveniently passed through a door opening only 2' 8" wide, leaving room for access to the closet. Furthermore, the support is provided with a single 25 strut only, which is inclined to the vertical to materially strengthen the mechanism. Further, the device is simple and compact in construction, economical to manufacture, extremely efficient in operation, and obviates the use of castors.

30 It is obvious that various changes and modifications may be made in the details of construction and design of the above specifically described embodiments of my invention without departing from the spirit thereof, such changes and modifications being restricted only by the 35 scope of the following claims.

Having thus described my invention, what I claim as new and desire to secure by Letters Patent, is:

40 1. A wallbed comprising a bed frame, a door frame, brackets on said frames, upper and lower arms pivoted to said bed frame and said door frame brackets, and means including a cam and cam follower connected to said frames for controlling the movement of said bed frame, whereby it pivots about the inner and outer ends of said arms to pass through the door frame.

2. In an apparatus of the class described, the 50 combination with a bed frame, of a floor plate and door frame bracket disposed in vertically spaced relation, upper and lower bed frame supporting arms pivotally mounted on said floor plate and door frame bracket with their pivots in vertically aligned relation, upper and lower brackets on said bed frame pivotally mounted on the outer ends of said arms, a lever pivotally connected to the lower arm adjacent its inner end disposed on the underside thereof, said lever having an offset 55 therein at its pivoted end to permit the swinging of its pivot to opposite sides of the pivot of said arm, said lever being provided with a cam follower, a cam coacting with said follower and having a straight portion at its inner end adapted to receive the follower when the bed frame is in its inner position, and a link connecting the said lever to said bed frame whereby the pivotal movement of said bed frame on said arms is automatically controlled when the arms are swung on their pivots.

60 3. In an apparatus of the class described, the combination with a bed frame, of a floor plate, and door frame bracket disposed in vertically spaced relation, upper and lower bed frame supporting arms pivotally mounted on said floor plate

and door frame bracket with their pivots in vertically aligned relation, upper and lower brackets on said bed frame pivotally mounted on the outer ends of said arms, a lever pivotally connected to the lower arm adjacent its inner end, 80 said lever being provided with a cam follower, said floor plate having a cam coacting with said follower, and a link connecting the outer end of said lever to said bed frame whereby the pivotal movement of said bed frame on said arms is controlled when the arms are swung on their pivot from collapsed to extended position, and vice versa.

4. In an apparatus of the class described, the combination of a bed frame, a floor plate, a pair of pivotally mounted vertically spaced connected bed frame supporting arms, one of said arms being mounted on said floor plate, said arms being pivotally connected to said bed frame at a central point, and means for controlling the position of 95 said bed frame on said arms as the arms are swung on their pivots consisting of a lever pivotally mounted on the lower arm and provided with a cam follower, said floor plate having a co-acting cam controlling the movement of said lever 100 on its pivot, and a link connecting said lever to said bed frame whereby the pivotal movement of the bed frame on said supporting arms is controlled.

5. In an apparatus of the class described, the 105 combination with a bed frame, of upper and lower pivoted arms on which said bed frame is pivotally mounted centrally of the bed frame, a lever pivotally connected to the lower arm adjacent its inner end and disposed on the underside thereof, 110 said lever having an offset therein at its pivoted end to permit the swinging of its pivot to opposite sides of the pivot of said arm, said lever being provided with a cam follower, a cam coacting with said follower and having a straight portion at its inner end adapted to receive the follower when the bed frame is in its inner position, and a link connecting the said lever to said bed frame whereby the pivotal movement of said bed frame on said arms is automatically controlled when the arms 115 are swung on their pivots.

6. In an apparatus of the class described, the combination with a bed frame, of upper and lower pivoted arms on which said bed frame is pivotally mounted centrally of the bed frame, a lever pivotally connected to the lower arm adjacent its inner end and disposed on the underside thereof, 125 said lever having an offset therein at its pivoted end to permit the swinging of its pivot to opposite sides of the pivot of said arm, said lever being provided with a cam follower, a cam coacting with said follower, and a link connecting the said lever to said bed frame whereby the pivotal movement of said bed frame on said arms is automatically controlled when the arms are swung on their 130 pivots.

7. In an apparatus of the class described, the combination with a bed frame, of upper and lower pivoted arms on which said bed frame is pivotally mounted, a lever pivotally connected to one arm 140 adjacent its inner end, said lever having an offset therein at its pivoted end to permit the swinging of its pivot to opposite sides of the pivot of said arm, said lever being provided with a cam follower, a cam coacting with said follower, and a 145 link connecting the said lever to said bed frame whereby the pivotal movement of said bed frame on said arms is automatically controlled when the arms are swung on their pivots.
